UNITED STATES PATENT OFFICE.

AARON HORTON AND SALYER HORTON, OF COLEMAN, MICHIGAN.

DISH WASHING APPARATUS.

1,170,261.

Specification of Letters Patent.

Patented Feb. 1, 1916.

Application filed December 17, 1914. Serial No. 877,743.

To all whom it may concern:

Be it known that we, AARON HORTON and SALYER HORTON, citizens of the United States, residing at Coleman, in the county 5 of Midland and State of Michigan, have invented certain new and useful Improvements in Dish-Washing Apparatus, of which the following is a specification.

This invention relates to washing apparatus and more particularly to an apparatus 10 for washing large quantities of dishes and other utensils in a rapid and efficient manner.

It is one aim of the invention to provide 15 an apparatus of the class described which will effectually cleanse the dishes and other utensils without likelihood of breaking, denting or otherwise injuring the same.

Another aim of the invention is to so construct 20 the machine as to adapt it to accommodate dishes and other utensils of various sizes and shapes and to subject all portions of the surfaces of the same to the action of the water or suds within the machine.

Another aim of the invention is to provide 25 a dish washing machine of such construction that no special care will be required when placing the dishes or other utensils within the machine, either as concerns their position of disposal or their proximity to each other.

The invention further aims to provide for 30 the positive delivery of the washed dishes or other utensils from the machine and to 35 provide against likelihood of any of the articles becoming lodged within the machine which would necessitate stopping the operation of the machine to permit of their removal.

It is another aim of the invention to provide 40 within the machine novel means for creating a forceful current of water circulating about the dishes and utensils passing through the machine so that the currents 45 of water will be caused to rush over the entire surfaces of the dishes thereby cleansing all portions thereof, and incidentally the means provided is adapted to maintain the water in a sudsy condition.

The invention has for a further object to 50 provide means whereby the tank of the

washing apparatus may be drained of scum or suds when any considerable or undesirable quantity has accumulated.

Further the invention has as its object to 55 so construct and arrange the washing apparatus that the dish conveying portion thereof may be readily swung clear of the tank whenever desired.

The invention also contemplates providing 60 the tank of the apparatus with a hinged cover which, while provided with openings in its walls for the introduction and removal of the dishes and other utensils to be washed, will serve effectually to retain the steam 65 from the heated water within the apparatus and prevent lowering of the temperature of the water and also render it unlikely that the person or persons using the apparatus will be subjected to inconvenience due to 70 heat or splashing of the water.

In the accompanying drawings: Figure 1 is a vertical longitudinal sectional view through the apparatus embodying the present invention. Fig. 2 is a vertical transverse sectional view therethrough taken approximately on the line 2-2 of Fig. 1. Fig. 3 is a vertical transverse sectional view through a portion of the wheel about which the dishes are carried in the tank of the apparatus. Fig. 4 is a perspective view of one end of one of the spokes of the wheel. Fig. 5 is a view partly in side elevation and partly in section through the device illustrating the cover therefor in raised position 80 and the conveyer and its supporting frame also raised.

Corresponding and like parts are referred to in the following description and indicated in all the views of the accompanying 85 drawings by the same reference characters.

The tank of the apparatus is mounted 90 within a frame including spaced sides, indicated by the numeral 1, and supported by legs 2, these sides preferably also constituting 95 the side walls of the tank. The bottom wall of the tank at the receiving and discharge end thereof is inclined downwardly toward the opposite end, as indicated at 3, and beyond its inclined portion is downwardly curved, as at 4, throughout the remainder of its length, the curved portion 100

of the bottom merging with the rear end wall of the tank, which wall is indicated at 5. It will be observed, by reference to Fig. 1 of the drawings, that the rear portion of the tank is much deeper than the forward portion thereof and it is in the rear portion that the dishes and other utensils are to be subjected to the action of the soapy water. The tank is provided with a cover including 16 sides 6, a front end wall 7, a rear end wall 8, and a top 9, and this cover is hinged at its forward end, as at 10, to the forward end of the portion 3 of the bottom of the tank so that the cover may be swung upwardly 15 to permit of access to the exterior of the tank. To permit of the introduction of the dishes and other utensils to the tank, in a manner which will be presently explained, one side wall of the cover is provided with 20 an opening 11 and the other side wall is provided with an opening 12 through which the washed utensils are to be discharged and the openings 11 and 12 are located at the forward end of the said cover.

25 The apparatus includes means for conveying the dishes and other utensils placed within the tank into the deeper rear portion thereof and through the water contained therein, this conveying means being further 30 arranged to carry the washed dishes or utensils toward the front end of the tank and through the opening 12, and this portion of the apparatus is mounted in a frame including side members 13 provided at their forward ends with upright portions or standards 14 and adjacent the said standards 14 with other standards, indicated at 15, the rear ends of the side members 13 being connected by a cross bar 16 which constitutes 35 a handle, as will be presently explained. A shaft 17 is journaled at its ends in suitable bearings 18 mounted at the forward corners of the tank and the ends of this shaft project through the openings in the portions 14 of the side members of the frame, whereby 40 to connect the frame for swinging movement about the shaft 17 as an axis. Mounted for sliding movement upon the opposing sides of the portions 14 of the frame at the 45 upper end of the said portions, are bearing plates 19 in which are journaled the ends of a shaft 20, and these bearing plates are provided with downwardly extending stems 21 which fit slidably through bracket ears 22 50 upon the said standards 14, the bearing plates being yieldably supported in elevated position by means of springs 23 fitting upon the said stems and bearing at their lower ends upon the bracket ears. It will be apparent at this point that the shaft 20 is supported for rotation and is yieldably held in elevated position, and the purpose of so mounting the shaft will be presently explained. A shaft 24 is mounted at its ends 55 in bearings located at the lower ends of the

standards 15 and this shaft is provided with sprocket gears 25 for a purpose to be presently explained. Also for a purpose which will be presently pointed out, the shaft 17 has mounted thereon sprocket gears 26 and 70 the shaft 20 is provided with sprocket gears 27.

In order to brace the members comprising the frame, brace rods 28 extend between the standards 15 and between the side members 75 of the frame between the shafts 17 and 24.

The apparatus includes an endless conveyer including sprocket chains 29 which are trained over the gears 25, 26 and 27 and which pass about a wheel forming a part of 80 the apparatus, and which is mounted within the frame above described, and these chains support between them a foraminotis apron 30 which is preferably of wire mesh material, although any other material suitable 85 for the purpose may be employed.

The wheel above mentioned comprises spaced hubs 31 which are fixed upon the ends of a shaft 32 journaled for rotation in the side members 13 of the frame at a point 90 between the shaft 24 and the cross bar 16, and tubular spokes 33 radiate from each of the hubs 31. Each of the spokes 33 is formed in its inwardly presented side with an opening 34 and arranged within each 95 spoke is a spring 35, the inner ends of the springs being secured within the spokes and their outer ends being connected to the ends of chains or other suitable flexible elements 36. Each of the chains 36 extends between the outer ends of the springs within corresponding ones of the spokes at opposite sides of the wheel and the said chains are trained over pulleys 37 journaled within the tubular spokes opposite the openings 34, the portions of the chains extending between the pulleys being normally held taut by the said springs 35. It will thus be seen that the wheel comprises spaced sets of 100 spokes and that what may be termed the periphery of the wheel, comprises a series of transversely extending normally taut elements. An endless apron or belt 38, of a width substantially equal to the width of 105 the wheel, is trained about the wheel and supported by the said chains 36 and this belt or apron is also trained over a roller 39 mounted upon a shaft 40 journaled in 110 bearings at the upper ends of the standards 15, this roller extending transversely above the tank and being located at the lower rear corner of the opening 12. It will now be observed, by reference to Fig. 1, that the upper stretch of the apron 38, or, in other 115 words, that portion of the apron extending between the upper side of the wheel and the roller 39, is inclined downwardly and forwardly to a slight degree and that it diverges in a forward direction from the 120 plane of the upper stretch of the apron 30. 130

It will also be apparent that the lower stretch of the apron 38 and lower stretch of the apron 30 between the lower side of the wheel and the shaft 24, converge 5 downwardly and rearwardly.

The purpose of providing the wheel with a yieldable periphery will be set forth in the description of operation of the apparatus, as also the manner in which the aprons 30 10 and 38 coöperate.

A beveled gear 41 is fixed upon the shaft 17 and meshes with a similar gear 42 at the lower end of a shaft 43 which is mounted in one of the uprights or standards 14. The shaft 43 is provided at its upper end with a beveled pinion 44, meshing with a similar pinion 45 at one end of a roller shaft 46 which is journaled in suitable bearings upon the standards 14 and 15 and about 15 which is passed an endless apron 47. The apron 47 is also passed about a roller 48 journaled in bearings 49 upon one side of the tank opposite the opening 12, so that the stretches of the apron 47 travel through 20 the said opening, the upper stretch of the apron moving in the direction of the opening so as to convey the dishes and utensils from the apparatus after the same have 25 been deposited upon the apron 47 from the upper stretch of the apron 38. In order that rotary motion may be imparted to the shaft 17 and through this shaft to the apron 30 and the wheel and through the wheel to the apron 38 and also in order that motion 30 may be imparted to the apron 47, a shaft 35 50 is mounted in suitable bearings upon the sides 1 of the main frame of the apparatus, and is geared by means of a belt 51 and pulleys 52 and 53 upon the shafts 50 and 40 55 17 respectively, and the said shaft 50 carries a worm gear 54 which is in mesh with a worm 55 upon a motor driven shaft 56. The shaft 56 is journaled at one end in a suitable bearing 57 mounted upon a trans- 45 verse support 58 located between the sides 1 and is driven, as for example, by pulleys 1 and a belt 59 from the shaft of a motor 60. In order that the dishes and other utensils placed upon that portion of the apron 50 55 30 which extends between the shafts 17 and 24, may be prevented from coming in contact with the ends of the spokes 33, guard plates 61 are mounted upon the standards 14 and 15 and the sides 13 of the frame 60 65 within the tank and have downwardly and rearwardly extending portions 62 which project between the side edges of the lower stretches of the aprons 30 and 38 in the manner clearly shown in Fig. 1.

It will now be apparent from the foregoing description that the dishes and other utensils to be washed are introduced through the opening 11 and placed upon that portion of the lower stretch of the apron 30 which 65 is traveling between the shaft 17 and the

shaft 24. Having been placed upon the said stretch of the apron, the dishes will be carried rearwardly and downwardly and will become engaged between the lower stretches of the said apron 30 and the apron 38 and will be carried by the movement of the said aprons and the rotation of the wheel through the water which is contained within the tank. As the dishes are carried about by the wheel, they will be lifted from the water and will subsequently be carried forwardly upon the upper stretch of the apron 38 and deposited upon the upper stretch of the apron 47, by which apron they are delivered through the opening 12 70 75 80 as previously pointed out.

By referring to Fig. 1 of the drawings, it will be observed that as the dishes or other utensils to be washed pass beneath the wheel, pressure will be exerted against the 85 apron 38 and that portion of the apron in contact with the dish or dishes will be forced inwardly against the tension of the springs 35 and the flexible connection 36, so that the dishes are firmly held between the aprons 30 90 and 38 in their passage about the wheel, although they are not liable to be broken or crushed, inasmuch as the wheel is, in effect, provided with a yieldable peripheral surface, which comprises the apron 38 and the 95 flexible connections 36 upon which the apron is supported.

At this point, it may be pointed out that the sprocket chains 29 pass over the ends of the spokes 33 in the manner shown in 100 Fig. 3 of the drawings, and that consequently the apron supported between these chains may be maintained in taut condition without, however, sagging or pulling inwardly upon the said flexible connections 36. 105

In order that the sprocket chains may be guided to position against the squared outer ends of the spokes, the spokes are provided at their said ends with beveled extensions 33'. However, the pressure exerted against the apron 30 by the dishes or utensils is compensated for by the springs 23 which yieldably support the shaft 20. Inasmuch as the aprons 30 and 38 are of foraminous material, such for example, as wire mesh, all portions of the dishes or other utensils being washed will be immersed in the water and subjected to the cleansing action thereof. It will also be apparent that as the dishes are carried forwardly upon the upper 110 120 stretch of the apron 38, they will be well drained before being deposited upon the apron 47.

Arranged below the portion 4 of the bottom of the tank is a false bottom 63 which 125 is preferably concentric to the said portion 4 and which is provided with a forward enlarged extension 64 having a partition 65 arranged horizontally therewithin, the said partition dividing the extension into a pas- 130

sage-way 66 and a chamber 67 and being spaced at its forward end from the forward end wall of the extension so as to form a port 68. The portion 4 of the bottom of the 5 tank at its juncture with the rear end wall 5 of the tank is formed with a port or opening 69 which is located substantially at the level of the water within the tank. The shaft 56 is journaled in a stuffing box 70 upon 10 the forward end wall of the extension 64 and the inner end of the shaft has fixed upon it a hub carrying a number of radially disposed blades 71. The bottom wall 4 of the tank is open, as at 72, between the passage 15 65 and the upper side of the extension 64, and it will be apparent that as the shaft 56 rotates, a current will be created in the water, by the movement of the blades 71, flowing from the openings 69 between the 20 bottom and false bottom, through the port or openings 68 into the tank through the opening 72, and it will be apparent that, inasmuch as the shaft 56 is rapidly rotated, the water will pass rapidly through the 25 opening 72 and forcefully through the stretches of the aprons 30 and 38 as they pass beneath the wheel and, of course, against the utensils or dishes confined between the said stretches of the aprons. In 30 order that the water within the tank may be heated, a burner 73 of any suitable type is provided and is supplied from any suitable source of gaseous or liquid fuel supply, and the nozzle of this burner projects into 35 a casing 74 having a water jacket 75 which is placed in communication with the interior of the tank by openings 76 formed in the false bottom 63. A number of water tubes 77 extend transversely within the casing 74 and are in communication at their ends with the water jacket 75, and, by reference to Fig. 1, it will be seen that the blast from the nozzle of the burner is directed against these tubes and against the 40 inner surfaces of the walls of the said casing so that the water within the tubes and water jacket will be heated to a high degree of temperature before entering the tank.

In order that the accumulation of suds and 45 scum may be removed from the surface of the water within the tank the rear end wall of the tank is formed with an opening 78 which is in communication with an overflow chamber 79, the rear and upper walls of 50 which form continuations of the false bottom 63 and the bottom wall of which comprises a partition 80. The chamber 79 has an overflow opening 81. It will be apparent, of course, that the opening 78 is located 55 above the normal water level within the tank and when it is desired to remove the accumulations of scum and suds from the surface of the water, an additional volume of water is supplied to the tank sufficient to 60 bring the water level up to the opening 78,

whereupon the overflow through this opening and into the chamber 79 will carry off the accumulation.

From the foregoing description of the invention it will be seen that there is provided 70 an apparatus which may be employed to rapidly and effectually cleanse a large number of dishes or other utensils without any likelihood of injury to the same.

By providing the cross piece 16 and by 75 mounting the conveyer apparatus in the frame of which this cross piece constitutes a part, the cross piece may be grasped and the frame may be swung upwardly so as to position the entire conveying apparatus exterior 80 of the tank.

It will be understood that due to the high temperature of the water and the rapid flow of the same past the dishes supported upon the conveyer, it will be unnecessary to 85 subsequently rinse and wipe the dishes, particularly, inasmuch as they are thoroughly drained before being exposed to cooler air exteriorly of the machine.

By reference to Figs. 1 and 5 of the drawings, it will be observed that the opening 12 in the cover extends entirely to the lower edge of the side in which it is formed and that when the cover is in lowered position, the opening 12 will be partly closed by a 95 plate 12' projecting upwardly from the corresponding side of the body of the casing.

It is preferable that a shelf 11' be arranged at the lower side of the opening 11, upon which the dishes may be disposed preparatory to being slid onto the moving apron.

Having thus described the invention, what is claimed as new is:

1. In washing apparatus, a tank, conveyer 105 aprons traveling in said tank, the stretches of the aprons traveling in contact throughout a portion of their lengths and for the remainder of their lengths traveling in spaced relation, the first-mentioned length 110 of one of the aprons being yieldably supported.

2. In washing apparatus, a tank, a rotary member mounted within the tank and having a yieldable peripheral surface, a conveyer 115 apron traveling about the said member and in contact with the said surface, and a second conveyer apron traveling in contact with the first mentioned apron.

3. In washing apparatus, a rotary member having radially yieldable elements comprising its peripheral surface, a conveyer apron traveling in contact with said surface, a second conveyer apron traveling in contact with the first mentioned apron, and means 125 for supplying water to the said aprons and to the said surface.

4. In washing apparatus, a rotary member having a peripheral series of radially yieldable elements, a conveyer apron sup- 130

- ported by and traveling upon the said elements, a conveyer apron having a portion of its length traveling in contact with the first-mentioned apron, and means for supplying water to the said aprons.
5. In washing apparatus, a rotary member having transversely extending peripherally located elements adapted to be radially sagged, means yieldably resisting sagging of the said elements, a conveyer apron traveling about and supported by the said elements, a second conveyer apron traveling in contact with the first mentioned apron, and means for supplying water to the said apron.
10. In washing apparatus, a rotary member having a peripheral series of transversely extending flexible elements, means connected with the elements and yieldably resisting inward radial sagging thereof, a conveyer apron traveling about and supported by the elements, a second conveyer apron having a portion of its length traveling in contact with the first-mentioned apron, and means 20 for supplying water to the aprons.
15. In washing apparatus, a rotary member including spaced series of spokes, springs arranged upon the spokes, flexible elements connecting the springs upon correspondingly located ones of the spokes, and having portions extending transversely between the said spokes and yieldable in the direction of the axis of the member, a conveyer apron supported by and traveling about the said 25 portions of the flexible elements, a second conveyer apron having a portion of its length traveling in contact with the said portion of the first-mentioned apron, and means for supplying water to the aprons.
30. 8. In washing apparatus, a rotary mem-
- ber having a yieldable peripheral surface, a tank in which the member is rotatably mounted, a foraminous conveyer apron traveling in contact with said surface, and a second conveyer apron traveling in contact with the first mentioned apron.
9. In washing apparatus, a tank, a rotary member having a yieldable peripheral surface, the said member being mounted within the tank, a foraminous conveyer apron traveling in contact with said surface, the upper stretch of said apron constituting a draining surface, and a second foraminous conveyer apron having a portion of its length traveling in contact with the said portion of the first-mentioned apron.
10. In washing apparatus, a casing including a tank, a rotary member mounted in the tank and having a yieldable peripheral surface, a conveyer apron traveling in contact with said surface, a moving apron onto which the upper stretch of the conveyer apron is arranged to discharge, the casing being provided in one side with an opening opposite the said moving apron, and a second conveyer apron having a portion of its length traveling in contact with the upper stretch of the first-mentioned apron, the casing being also provided in one wall with an opening for admission of the articles to be 60 placed upon the lower stretch of the second-mentioned apron.
65. In testimony whereof we affix our signatures in presence of two witnesses.
